UNITED STATES PATENT OFFICE.

ALPHONZO B. BOWERS, OF WASHINGTON, DISTRICT OF COLUMBIA.

APPARATUS FOR DREDGING AND TRANSPORTING SPOIL.

SPECIFICATION forming part of Letters Patent No. 484,763, dated October 18, 1892.

Original application filed December 9, 1876. Renewed April 16, 1879. Divided and application filed April 29, 1885, Serial No. 163,888. Again divided and this application filed January 5, 1886. Serial No. 187,638. (No model.)

To all whom it may concern:

Be it known that I, ALPHONZO B. BOWERS, civil engineer, of San Francisco, California, now residing in Washington, District of Columbia, have invented an Improvement in Apparatus for Dredging and Transporting Spoil, for which application for Letters Patent, filed December 9, 1876, was renewed April 16, 1879, and is still pending, in part, before the Patent Office, Letters Patent Nos. 318,859 and 318,860, for two divisions of this application having been issued to me May 26, 1885. A third division embracing all of the aforesaid original not included in the Letters Patent above specified was filed April 29, 1885, and bears the Serial No. 163,888. This application is a fourth division of the aforesaid original or a first division of said third division. It also consists in part of a first division of an application filed June 30, 1883, and having the Serial No. 99,678.

It consists, mainly, of a peculiar rotary excavator that delivers its spoil inward through itself to a suction-pipe; an improved device for mounting and actuating the excavator; a suction-pipe, ladder, and excavator connected with the boat by a universal joint and supported by a crane or by an arm, spar, jib, beam, or boom having a lateral swing, whereby said pipe, excavator, and support are enabled to swing laterally, either with or independently of the hull, and make a wide or narrow swing at the will of the operator; a vertical feeding or fleeting anchor also mounted on a swinging derrick or frame and arranged to vary the amount of forward feed in varying conditions of work; a device for relieving the flexible sections of the pipes from the strain of holding the rigid sections in place, with details of construction, for all of which this and the accompanying drawings are a specification.

Figure 1 is a vertical and longitudinal section of a dredge-boat and a side view of some of my improvements. The ladder on which the suction-pipe is usually mounted is omitted in this figure to show more clearly the arrangement for actuating the excavator and because under some circumstances it is not necessary. Fig. 2 shows the swinging crane-post and the hydraulic hoist that raises, low-

ers, and holds the excavator. Fig. 3 is a plan of the hull and of most of the improvements claimed in this application. Fig. 4 shows in black a cross-section of the bell-mouth suction-pipe, tubular bearing of the excavator-shaft, and the ribs that support this bearing. It also shows the inner end of the excavator and anti-friction rollers sometimes used to carry this end. Fig. 5 shows details of construction and mode of mounting and actuating the excavator. Fig. 6 shows the collar-and-groove thrust-bearing G of shaft F, the cap being removed to show details of construction. Fig. 7 is a side, and Fig. 8 a top, view of the pump and a portion of two suction-pipes, showing how by means of suitable trussing and bracing these pipes may be made to constitute one form of the ladder usually, though not always, employed to support the excavating device. These pipes, as shown in Figs. 7 and 8, swing on hollow trunnions provided with glands, through which passes the shaft of the pump, the pipes also passing through glands to the suction of said pump. This arrangement forms a strong ladder, (and by the term "ladder" in both description and claims I mean a structure consisting of at least two longitudinal members united by cross bars or beams and serving as a support to the suction-pipe or to the excavator, or to both.) Either pipe may be constructed to carry water and spoil, or both may be so constructed, though a single conduit with any suitable form of trussing and bracing is preferable, (for one form of which see ladder I, yoke J, and pipe C, Fig. 3, which shows, also, the further modification of a lateral swing independent of the boat.)

A is a floating vessel that carries the engines, boilers, and excavating apparatus.

B is a pump that draws the spoil up the suction-pipe and sends it through the discharge-pipe to a place of delivery. It is placed below the water-line in order to secure the full atmospheric pressure, supplemented, if desired, by the weight of water above the suction-passages, and also to enable those passages to be submerged to prevent leakage of air in case said passages should prove to be not wholly air-tight.

C, Figs. 1 and 3, is a suction-pipe connected

with the pump B. It is provided near its outer end with seats, on which are mounted the motor H, that actuates the excavator, and the collar-and-groove thrust-bearing G; also, 5 a short detachable mouthpiece curved, as shown, Fig. 5, to allow the excavator-shaft to pass through a long tubular bearing to the outside of the pipe and to the motor H. The mouth of this curved section is enlarged to 10 compensate for the space occupied by the tubular bearing and its supporting-ribs. The swinging outer section of this pipe is connected with the boat and inboard section by a strong universal joint D, hereinafter more fully described. 15 This pipe is usually mounted on a ladder I and yoke J, Fig. 3, though the ladder may be constructed to perform the office of both ladder and yoke. In some instances I prefer to make them separate and detachable, so 20 that the boat may be lightened by the removal of the ladder when making a shallow cut in still water and loose material. Both ladder and yoke swing on strong trunnions K K or equivalent joints. These trunnions 25 project from opposite sides of the swinging derrick-post, and with the ladder or yoke and swinging post form an open universal joint D, leaving the ladder and pipe free to move in any direction, and thus accommodate them- 30 selves to the movements of the hull when working in rough water. Through this open universal joint passes a section of flexible suction-hose, uniting the swinging with the inboard section of pipe. This flexible section 35 is of sufficient length to make easy curves in accommodating itself to the movements of the pipe and crane and is used to avoid the abrupt angles and irregular waterway of a hollow ball-and-socket or other hinged joint.

40 C' is a discharge-pipe. D D are open universal joints securely mounted on opposite ends of the boat. On these joints are mounted the swinging sections of the suction and discharge pipes. 45 These joints relieve the flexible sections D' of these conduits from the strain of holding the inner ends of the rigid swinging sections in their proper positions.

D' D' are flexible sections of the conduits 50 C and C'. They may be made of leather, rubber, canvas, or other suitable material, the one forming a portion of the suction-pipe being constructed to resist external (and the one on the discharge-pipe internal) pressure. The 55 central portions of these flexible sections should be coincident with the axes of the joints D D to give equal facility of curvature in all directions. The friction of mud and water passing through the smooth easy curves and un- 60 form water-way of a flexible section is much less than in the abrupt angles and irregular water-ways of hollow ball-and-socket or other hinged joints, for which reason flexible sections are much preferable, though I confine 65 myself to no particular form of universal joint.

E is any device working with a side feed across the cut and delivering its spoil inward

through itself to a suction-pipe. It is not necessarily rotative, though the rotary is thought to be its best form.

70 Specific claims for non-rotative devices are made in other applications and other divisions of the application filed June 30, 1883, now pending. It is here shown in one of its many rotary forms, and it, with the curved 75 mouthpiece of the suction-pipe, the motor H, and ladder, may be omitted in loose semi-liquid material at a great reduction in the cost of the machine, though at the expense 80 of much of its efficiency.

85 Either end or both ends of the excavator here shown may be dished, substantially as represented in Fig. 5, to guide the spoil toward the mouth of the suction-pipe and contract the water-way through the excavator to prevent the admission of too much water.

90 In the divisions of the application embraced in Letters Patent Nos. 318,859 and 318,860 already issued, the excavator is shown with a conical hub fitting into a hollow conical casing in the outer end of a hollow inner chamber, around which the excavator revolves. In this division said inner chamber is omitted. The excavator is of a different form. The hub 95 abuts against the bearing j and is provided with no casing. The excavator is mounted on a shaft F, Fig. 5, passing through a tubular bearing in the mouth of the suction-pipe, and its inner end runs on antifriction-rollers a, that travel on and around said pipe.

100 F is the driving-shaft of the excavator. Its diameter may be slightly reduced at the opening b to allow a thin film of water to be forced or drawn in through this opening to lubricate the bearing, but more particularly to keep 105 out grit by the passage of a constant stream of water, as the construction of the excavator is such as continuously to throw the spoil against said bearing. Instead of weakening the shaft by cutting it down, it may be enlarged by shrinking on a thin sleeve of brass or bell-metal to form the bearing, or the bearing-tube may be slightly enlarged at the aperture b to permit the water to pass around the shaft and have free access to the entire bearing. 110 With no special provision other than the aperture b the bearing might be sufficiently lubricated and the grit probably kept out by forcing in water from a pump on the boat. The shaft may be provided with a 115 gland c as a further precaution against the admission of grit.

G is a collar-and-groove thrust-bearing to prevent longitudinal movement of the shaft F.

H is a hydraulic motor acting directly on 120 the excavator-shaft. It may be placed near the excavator to avoid friction in the several bearings of a long shaft resulting from any sagging of the ladder or pipe on which these bearings must be placed and to allow the use 125 of a lighter ladder or other rigid connection than would otherwise be necessary. This motor is actuated by a force-pump on the boat, with which it is connected by a pipe or

hose, (not shown,) and may be mounted on either ladder or pipe, preferably on the pipe. By incasing this motor and its pipes in a suitable housing or placing it above water at the 5 upper end of the suction-pipe steam instead of water pressure might be used after gearing down to the proper speed, and therefore I confine myself to no specific motor, the hydraulic being usually preferred on account of 10 its reduced size, direct action, greater simplicity of arrangement, the ease and certainty with which its speed can be regulated to suit different conditions of work, reduced weight, and diminished liability of getting out of 15 pair.

I is a rigid connection between the outer end of the suction-pipe or other device on which the excavator is mounted and a boat swinging on a vertical anchor or other contained center of oscillation, or between said outer end and a swinging or turning crane-post, Figs. 1, 2, and 3, or other swinging or turning device to which I is hinged. It is represented in the drawings as making, in 20 connection with the swinging device, a universal-joint connection with the hull. In Fig. 3, with tie-rods T in place, and in Figs. 7 and 8 it swings independently of the boat only in a vertical plane. It may be a ladder consisting 25 of sides and cross-pieces with or without braces, or it may be any suitable trussed framework, a spar, beam, or boom, or even the suction-pipe itself, and yoke J, as in Fig. 1, if said pipe and yoke be made strong 30 enough for this purpose. It may be hinged in any suitable manner to a boat swinging on a contained center of oscillation or to any swaying device, by means of which it becomes capable of being made to swing in vertical and lateral planes. In the device shown 35 in Fig. 1, and also in Fig. 3, when the tie-rods T are removed the axes of vertical and lateral oscillation intersect, thus forming an open universal joint, requiring but one flexible 40 section to accommodate both vertical and lateral movements, and this is often the preferable form; but in some forms of construction these axes do not intersect, and when they are several feet apart, instead of 45 one flexible section it is usually advisable to use two short sections, one to accommodate the vertical, the other the lateral swing.

The general conception of the device I is a rigid connection of the outer end of the suction-pipe with the boat, the crane-post, or other swinging device. A specific form of it 50 is the ladder above described.

J is a fork or yoke connecting the rigid swinging section of the suction-pipe or the 55 ladder, or both, with the trunnions K K, to which they are hinged. This fork should be long enough to allow the center of the flexible section to be in line with the trunnions K K.

L is a swinging crane-post or other swinging device that, in connection with yoke J, ladder I, or other equivalent construction, 60

forms a universal or double joint or joints, by means of which the suction-pipe is securely connected with the hull and made capable of being swung in vertical and lateral planes in 70 front of and independent of any swing of the boat.

L' is an arm, spar, jib, beam, or boom that may be mounted in any manner capable of supporting the excavator and allowing it to 75 have a lateral swing. It is shown in the drawings as hinged to the crane-post to allow a vertical adjustment and to swing laterally with said post.

L² is a swinging derrick or frame with hollow post, through which passes the pivotal anchor V, which, being carried by the boat, may be termed a "contained pivot" or "center of oscillation," on which the dredger swings when cutting a wide channel. Through 80 a traveler on this derrick passes the fleeting or feeding anchor V'. On the derrick-post, Fig. 1, is mounted the windlass f, around which wind the lines g g for moving the dredge forward after dropping V' and raising 85 the other vertical anchor. By turning the windlass the dredge may be fed forward until V' occupies in relation to the derrick the position indicated by the outlines V², or it may be fed forward any fractional part of 90 this distance. The anchor V is then dropped into the mud and V' (indicated by the outlines V²) is raised to be out of the way of the discharge-pipe. The windlass f is then released from its ratchet and V' falls back to 95 its former position near the hollow derrick-post. I do not confine myself to this form of construction, as any convenient methods of raising the anchors and of moving the traveler and fleeting or feeding anchor may 100 be used instead of those here shown and described.

M M are trunnions on opposite sides of the crane-post, on which the arm L' may be mounted.

N is a hydraulic hoist with which (and the cable h) the ladder, suction-pipe, and excavator are raised, lowered, and held in working position.

O O are anchors for holding the hull in a 115 stationary position when cutting a narrow channel by swinging the excavator laterally in front of the boat.

O' O' are hollow cylinders passing through the hull for the reception of the anchors O.

O² O² are masts provided with blocks, tackle, and windlass o for raising the anchors O V V'.

P P are winding devices for swinging the excavator, suction-pipe, and crane when making a narrow cut in front of the hull and for 125 swinging the hull itself when cutting a wide channel.

Q Q are cables passing from winding devices on the hull to blocks e e, attached to the arm L', ladder I, or suction-pipe, and thence 130 to the anchors R R', to which they may be secured; or they may pass through blocks at-

tached to these anchors and back to the suction-pipe or ladder, or rigid connection, substantially as shown.

R R are preferably of the type termed 5 "mushroom-anchors," though any anchors capable of holding their position will answer.

S S shows the arc through which the excavator swings on the crane, and s s a portion of the arc traversed when swinging with the 10 hull on the anchor or contained pivot V.

T T are detachable tie rods or guys to prevent the excavator from swinging independently of the hull when cutting a wide channel by swinging on the anchor V.

15 U is a device for indicating at the arm L' the depth at which the work is progressing.

Z Z' are valves for excluding water or mud when the pump B is opened for examination or repairs.

20 This machine can be successfully operated only when the excavator is below the surface of the water. In some cases the material to be moved rises above said surface and undercutting is necessary. In some such cases, if

25 the machine should be fed forward to undercut the full length of the excavator, an insufficient supply of water would enter the suction-pipe, which would consequently become choked. In such cases the machine may be 30 fed forward for the first swing in each series (1, 2, 3, and so on, Fig. 1) only one-half the length of the excavator, the remaining half being cut by again feeding forward and making a second swing before lowering the excavator.

35 In very hard and also in very rooty or fibrous material the undercut portion may not always break off and fall as the excavator passes from under it. For such cases a double-edged bracket m or other suitable support projects from near the lower end of the suction-pipe to a point over the outer end of the excavator. To the outer end of this support is hinged the bar l. The lower part of 40 this bar is provided with a cutting-edge on each side, that, swinging in either direction, severs from the bank the undercut material left by the excavator, causing it to fall partly on and partly behind said excavator. The upper end of the bar l slides freely in a slot

45 in the outer end of the boom L' as the excavator is raised and lowered. This upper end may be provided with a figured scale that shows at the boom or elsewhere, as desired, the depth at which the work is progressing.

50 This scale also shows the operator when the cutter has been lowered the proper depth for each successive swing, as well as when the required depth of cut has been attained.

55 This application, consisting of divisions of two other applications, as hereinbefore stated, (to wit, a division of the third division of the application filed December 9, 1876, and a division of the application filed June 30, 1883,) shows features described and claimed in Letters Patent Nos. 318,859 and 318,860 for other divisions of the original application, and reference is here made to these Letters Patent

for a further exposition of my improvements and claims.

In this division of the aforesaid applications I claim—

1. A hollow rotary excavator with inward delivery, in combination with a suction-pipe, said excavator being provided with a dished end constructed to guide the spoil toward the 75 mouth of said pipe.

2. A hollow rotary excavator with inward delivery and uncased hub, in combination with a suction-pipe and a shaft having a bearing close to said hub.

3. A rotary excavator mounted on a shaft provided with a collar and grooved thrust-bearing, in combination with a suction-pipe.

4. A rotary excavator mounted on a non-rotative suction-pipe and provided with anti-friction-roller bearings, said bearings being constructed substantially as shown and described.

5. A hollow rotary excavator with inward delivery through itself to a suction-pipe, said excavator being mounted on a shaft provided with a device for washing out grit from the bearing of said shaft.

6. In combination, a hollow rotary excavator with inward delivery, through itself, mounted on a shaft provided with a device for excluding grit from the bearing of said shaft, and a suction-pipe.

7. A rotary excavator mounted on a shaft having a bearing within a tube passing from the hub of said excavator to a point outside of the suction-pipe and in combination with said pipe.

8. A rotary excavator mounted on a shaft provided with a long tubular bearing, said shaft having a reduced portion within said tube and a pipe for introducing water to said reduced portion.

9. In combination, a suction-pipe, a hollow rotary excavator with inward delivery through itself to said pipe and mounted on a shaft driven by a motor acting directly on said shaft.

10. A hollow rotary excavator with inward delivery through itself, in combination with a suction-pipe and a motor mounted on said pipe.

11. A hollow rotary excavator with inward delivery through itself, in combination with a suction-pipe mounted on the yoke J or equivalent joints.

12. A rotary excavator with inward delivery through itself, in combination with a suction-pipe and the ladder constructed and arranged to swing in vertical and lateral planes, as described.

13. In combination, the ladder, as described, suction-pipe, and a hollow excavator that delivers its spoil inwardly through itself to and rotates independently of said pipe.

14. A rotary excavator with inward delivery through itself, in combination with a suction-pipe.

15. A rotary excavator with inward delivery

through its side and arranged to work with a side feed, in combination with a suction-pipe and the rigid connection I, hinged to swing in a vertical plane:

5 16. A rotary excavator with inward delivery through itself, in combination with a suction-pipe mounted on a device that swings in a vertical plane, said pipe being provided with a flexible section D' to accommodate said 10 swinging.

17. A hollow rotary excavator with inward delivery through itself, in combination with a non-rotating suction-pipe mounted to swing independently of the boat in a vertical plane 15 and in planes perpendicular to said vertical plane, with means for making said swings.

18. A suction-pipe mounted to swing on trunnions or equivalent joints and provided with a flexible section D' to accommodate 20 said swing.

19. In combination, a dredge-boat, pump, and a suction-pipe having an outer-swinging section mounted on a universal joint and a flexible section to accommodate said joint.

25 20. In combination, a dredge-boat, exhausting apparatus, and a swinging section of suction-pipe connected with said apparatus by a flexible section D', provided with a joint constructed and arranged to hold (and to relieve 30 said flexible section from the strain of holding) the swinging section in proper position.

21. In combination, a dredge-boat, exhausting apparatus, and a swinging section of suction-pipe connected with said apparatus by a flexible section and provided with a universal joint constructed and arranged to relieve said 35 flexible section from the strain of holding the swinging section.

22. In combination, a dredge-boat, pump, 40 and a discharge-pipe having outside of said boat a section of said pipe mounted on a universal joint and provided with a flexible section D' to accommodate said joint.

23. In combination, a dredge-boat, non-rotating suction-pipe, and a hollow rotary excavating device with inward delivery through itself to said pipe, said excavator being arranged to swing in a lateral plane in front of and independently of a swing of the boat, 45 and with means for making said swing.

24. In combination, a dredge-boat, the ladder described, a non-rotating suction pipe, and hollow rotary excavating implement that delivers its spoil inward through itself to said 50 pipe.

25. In combination, a ladder, suction-pipe, and hollow rotary excavator with inward delivery through itself to said pipe.

26. In combination, a suction-pipe, ladder, 60 and hollow rotary excavator with inward delivery through itself to said pipe, said excavator being provided with side cutting-edges and devices that effect a side feed.

27. In combination, a suction-pipe, ladder, 65 and hollow excavator with side cutting-edges, and devices that effect a side feed.

28. In combination, a dredge-boat provided

with the ladder described, suction-pipe, and an excavating implement constructed to swing in vertical and lateral planes independently of said boat, with means for making said swing. 70

29. In combination, a dredge-boat, a ladder mounted to swing vertically and laterally on a crane, a suction-pipe supported by said ladder, an excavating implement connected by said pipe with a pump on the boat, said pipe being provided with a flexible section to accommodate the movements of the ladder and crane, means for raising and lowering the 80 ladder, and means for swinging it and the crane.

30. In combination, a dredge-boat, a ladder mounted to swing vertically and laterally on a crane, a suction-pipe supported by said ladder, an excavator that delivers its spoil inward through itself to said pipe, by which it is connected with a pump on the boat, said pipe being provided with a flexible section to accommodate itself to the movements of 90 the ladder and crane.

31. In combination, a dredge-boat, a ladder mounted to swing vertically on a crane, a suction-pipe supported by said ladder and connecting a rotary excavator with a pump 95 on the boat, said pipe being provided with a flexible connection to accommodate the movements of the ladder and crane.

32. A dredge-boat, a swinging crane connected thereto, a jointed suction-pipe mounted to swing with said crane and carrying an excavator, a pump connected to said suction-pipe, and means for raising, lowering, and swinging said suction-pipe, all combined substantially as described. 100 105

33. In combination, a dredge-boat, a suction-pipe mounted to swing vertically and laterally on a swinging crane, a pump on the boat, connected with the suction-pipe, said pipe being provided with a flexible section D', 110 that yields to its vertical and lateral movements, means for raising, lowering, and holding, and warping-lines connected with the outer end of said pipe and passing to winding-drums for laterally swinging said end. 115

34. In combination, a dredge-boat, a suction-pipe mounted to swing vertically on and laterally with a swinging crane, a rotary excavator connected by said pipe with a pump on the boat, said pipe being provided with a 120 flexible section D' to accommodate its vertical and lateral movements, and means for making these movements.

35. In combination, a dredge-boat, a rotary excavator mounted on a suction-pipe constructed to swing in vertical and lateral planes on a stationary universal joint, a laterally-swinging device for supporting the outer end of said pipe, and means for swinging the pipe and its swinging support. 125 130

36. In combination, a dredge-boat, a suction-pipe mounted to swing vertically and laterally on a universal joint, said pipe being provided with a flexible section D' to accom-

modate these movements, a rotary excavator connected by said pipe with a pump on the boat, a motor that actuates said excavator and swings with it and the pipe, and means for laterally swinging the same.

37. In combination, a dredge-boat, a suction-pipe mounted to swing vertically and laterally on a universal joint, said pipe being provided with a flexible section B' to accommodate these movements, a hollow rotary excavator with inward delivery through itself, connected by said pipe with a pump on the boat, a motor for actuating said excavator, and means for giving to said pipe and excavator said vertical and lateral swings.

38. In combination, a dredge-boat, a suction-pipe arranged to swing vertically and laterally in front and independently of the boat, detachable tie-rods arranged to hold said pipe from swinging laterally independently of said boat, and means for laterally swinging the pipe and boat together.

39. In combination, a dredge-boat, a suction-pipe and rotary excavator mounted to swing vertically and laterally in front of said boat, detachable ties to prevent said pipe and excavator from swinging laterally independently of the boat, and means for swinging the whole together.

40. In combination, a dredge-boat, an excavating device mounted to swing in front of the boat, means for preventing said device from swinging laterally independently of said boat, and means for swinging said device with the boat, said means being also adapted at will to swing the pipe independently of the boat.

41. In combination, a dredge-boat, excavating device, and a cable passing from a winding device to a block or sheave near the outer end of the apparatus that supports said excavating device and thence to an anchor in position to give a side swing as the cable is drawn inboard.

42. In combination, a dredge-boat, excavating device, and a cable passing from a winding device to a block or sheave near the excavator or point of resistance, thence to an anchored block in position to give a side swing as the cable is drawn inboard, and from said anchored block to near the end of the apparatus on which said excavating device is mounted, where the end of said cable is made fast.

43. In combination, a dredge-boat, a suction-pipe, and excavating device mounted on the outer end of a rigid support I, hinged to a swinging device L to swing in vertical and lateral planes, means for raising, lowering, and holding the outer end of this support, and means for laterally swinging the same.

44. In combination, a dredge-boat, a swinging arm L', a suction-pipe, a rotary excavator mounted on the outer end of a rigid support I, hinged at its inner end to the swinging device L to swing in vertical and lateral planes, means for raising, lowering, and holding the

outer end of this support, and means for laterally swinging the same.

45. In combination, a dredge-boat, a rotary excavating device, and non-rotating suction-pipe, said excavator being provided with a rigid support, said support being connected with the boat by a universal joint, and means for raising, lowering, and laterally swinging the outer end of said support.

46. In combination, a dredge-boat, a rotary excavator mounted on a non-rotating suction-pipe, said pipe being connected with the boat by a universal joint on which the pipe swings when at work, and means for raising, lowering, holding, and swinging the excavator and outer end of said pipe.

47. In combination, a dredge-boat, a rotary excavating device with inward delivery through itself, mounted on a non-rotating suction-pipe, said pipe being connected with the boat by a universal joint, and means for raising, lowering, holding, and swinging the outer end of said pipe.

48. In combination, a dredge-boat having a contained pivot or center of oscillation, a crane, a suction-pipe mounted on said crane and having a vertical and lateral swing, a pump on the boat connected with said pipe, this pipe being provided with a flexible section that yields to and permits said vertical and lateral movements.

49. In combination, a dredge-boat that carries a pivot or center of oscillation, a ladder that swings in a vertical plane and supports an excavating device, cables connected with said ladder, and means, in connection with said cables, for laterally swinging said boat on said pivot.

50. In combination, a dredge-boat that carries a pivot or center of oscillation, a ladder that swings in a vertical plane and supports an excavating device that works with a side feed, cables connected with said ladder, and means, in connection with said cables, for continuously swinging said boat from side to side on said pivot while said excavator is at work.

51. In combination, a dredge-boat, a swinging frame, and a fleeting spud carried by said frame, for feeding the boat forward as the work progresses.

52. In combination, a dredge-boat, a swinging derrick provided with a vertical anchor, means for raising, lowering, and holding said anchor, and means for moving it along the arm of said derrick.

53. In combination, a dredge-boat, a derrick having a hollow post, through which passes a vertical anchor, and means for raising, lowering, and holding said anchor.

54. In combination, a suction-pipe mounted to swing in a vertical plane, a rotary excavator that delivers its spoil inward through itself to said pipe, and a motor that actuates said excavator and swings with it and the pipe.

55. In combination, a suction-pipe mounted

to permit its outer end to swing in a vertical plane and in planes perpendicular to said vertical plane, said pipe being provided with a flexible section D' to accommodate these 5 movements, a rotary excavator connected by said pipe with a pump on the boat, a motor which actuates said excavator, and means for vertically and laterally swinging the same.

56. In combination, a suction-pipe which 10 swings in a vertical plane, a rotary excavator that delivers inward through itself to said pipe, and a motor that actuates the excavator and swings therewith.

57. In combination, a suction-pipe mounted 15 on a dredge-boat to swing in a vertical plane, said boat having a contained center of oscillation, means for swinging said boat on said center, a rotary excavator in connection with said pipe, and a motor that actuates said excavator and swings with it and the pipe.

58. In combination, an exhausting apparatus, a suction-pipe connected with this apparatus and mounted to swing with the device L', a rotary excavator in connection with 25 said pipe, and means for actuating said excavator.

59. In combination, an exhausting apparatus, a suction-pipe connected with this apparatus and mounted to swing on an arm, 30 spar, jib, beam, or boom L', a rotary excavator connected with said pipe, and a hydraulic motor that actuates said excavator.

60. In combination, a swinging derrick or crane, a suction-pipe provided with a rotary 35 excavator, means for actuating said excavator, means for raising, lowering, and holding it, and means for swinging it and the crane.

61. In combination, a derrick or crane, a suction-pipe provided with a rotary excavator 40 that delivers its spoil inward through itself to said pipe, means for raising, lowering, and holding the excavator, means for rotating it, and means for swinging it and the crane.

62. In combination, a dredge-boat, pump, 45 suction-pipe, hollow rotary excavator with inward delivery through itself, and a motor for actuating the excavator independently of the pump.

63. A swinging frame for dredging purposes, consisting of an upright open-centered post, an arm borne by said post, a frame or ladder pivoted to the post to swing in a vertical arc or plane, tackle connected to said arm to raise, lower, and hold the outer end of 50 said ladder, and bearings constructed to hold the post in its upright position and permit the frame to swing in a lateral arc or plane.

64. In combination, a dredge-boat, a swinging crane with hinged support carried there- 55 by, a suction-pipe connecting a pump on the boat with the excavator at the end of the lad-

der, and having a flexible section to accommodate the vertical movement of the ladder and the lateral movement of the crane.

65. In combination, a dredge-boat, a swing- 65 ing crane having the ladder, frame, or carrier of the excavating or dredging implement mounted thereon, a pipe having a universal joint in its length connecting the excavator with apparatus on the boat, so as to have movement in a vertical arc on the hinge of the carrier and in a lateral arc from side to side by the swing of the crane, winding-drum, and tackle connected with said drum and supporting the hinged carrier from the boom of 70 the crane.

66. In combination, a dredge-boat, a swing- 75 ing frame or ladder having adjustment in both vertical and lateral planes, a rotary excavator carried thereon, a suction-pipe ex- 80 tending from a pump on the dredge to the excavator, and provided with a joint or flexible section which permits said pipe to accommo- 85 date itself to the movements of the ladder or frame and to follow the same in the vertical and lateral planes, and a driving-shaft connected with actuating mechanism on the dredge, permitting movement and rotation of the excavator in unison with the movements of the ladder or frame.

67. In combination, an excavating implement, a swinging frame or excavator-carrier having adjustment in a vertical plane and a swinging movement in lateral planes, and a suction-pipe supported by the swinging car- 90 95 rier and having a flexible joint or section at the center of movement of the carrier.

68. In combination, a dredge-boat, anchoring devices to hold said boat in position for working, a swinging frame having move- 100 ment and adjustment in vertical and lateral planes, an excavator at the outer end thereof, and a suction-pipe connecting the suction-chamber of the excavator with a suction-pump below the water-line, whereby the suc- 105 tion space and passages are submerged when the pump is in operation.

69. In combination, an excavator that works with a side feed, a suction-pipe, and means to sever from the bank the material undercut 110 by said excavator as it swings from side to side.

70. In combination, an excavator, suction-pipe, and the cutting-bar l, substantially as and for the purpose specified.

71. In combination, an excavator, suction-pipe, and the cutting bar and scale l.
